UNITED STATES PATENT OFFICE.

JOHN G. CARLINET, OF PHILADELPHIA, PENNSYLVANIA, ASSIGNOR OF ONE-HALF TO GOTTLIEB F. BAUER, OF PHILADELPHIA, PENNSYLVANIA.

MOTOR.

SPECIFICATION forming part of Letters Patent No. 743,244, dated November 3, 1903.

Application filed April 2, 1903. Serial No. 150,811. (No model.)

To all whom it may concern:

Be it known that I, JOHN G. CARLINET, a citizen of the United States, residing in Philadelphia, Pennsylvania, have invented certain 5 Improvements in Motors, of which the following is a specification.

My invention relates to an improved device for the utilization of fluid under pressure to obtain rotary movement of any desired 10 form of apparatus, having for its object the production of a simple and efficient fluid-operated motor whereby the reciprocating motion of a plunger or plungers is transformed into rotary motion of a piece or structure designed 15 to be connected to any device to be operated. This object I secure as hereinafter set forth, reference being had to the accompanying drawings, in which—

Figure 1 is a side elevation of one form of 20 my improved motor, showing it as designed especially for use in connection with a rotary drill. Fig. 2 is a sectional elevation of the motor taken on the line 2 2, Fig. 1. Fig. 3 is a sectional elevation of the motor taken 25 on the line 3 3, Fig. 2. Fig. 4 is a plan view of the motor, taken on the line 4 4, Fig. 1. Fig. 5 is a plan view of the revoluble member 30 of my improved motor, showing the gripping-levers therefor; and Fig. 6 is a side elevation of my improved motor in position for operating a drill.

In the above drawings, 1 is a casting consisting of two cylinders open at the ends and connected by a substantially circular plate 7 35 and a portion 17, each of said cylinders being made in two parts held together by bolts 2, said bolts serving also to hold in place bushings 3 and 4, fitting within said cylinders. These bushings are closed at their 40 outer ends and are bored for the reception of a two-part plunger 5, which consists of two cylindrical end pieces united by an intermediate section 6, which is preferably square in section. The plate 7 extends between extreme 45 portions of the cylinders at a point below the plunger 5, and there are formed on said plate at points in the present instance ninety degrees from the line of action of the plunger lugs 8, which may be made depending 50 and are provided with threaded holes for the reception of headed bolts 9, serving as

pivots or fulcrums for connecting arms 10 and 10^a. These two arms extend from their respective pivots toward each other, and the squared portion 6 of the plunger is recessed 55 for the reception of their ends, there being longitudinally-elongated slots formed in them intermediate of said ends and the pivots 9, serving for the reception of pins or projections 11, fixed to and projecting from curved 60 levers 12 and 12^a, designed to operate within an annular recess 13^a, formed in the movable element 13 of the motor. Said movable element is rotatably supported on a projection or trunnion 14, formed integral with and projecting from the plate 7 of the cylindrical casting 1 at right angles to the line of action 65 of the plungers and being retained in position thereon by means of pins 15, which while fastened in the part 13 engage a groove 16, 70 formed in the trunnion 14, it being noted that the lower end of said trunnion is preferably made convex in form, so that its bearing upon the bottom of the cavity in the movable element is of relatively small extent. 75 It is understood that any other desired device may be employed between these two members for reducing the friction.

The curved levers 12 and 12^a are so formed that while freely movable within the annular 80 cavity around the axis of the trunnion 14 their ends carrying the projections 11 are also movable toward or from said trunnion, the result of this latter action being to cause a portion of the outer side of a lever to contact 85 with the outer side of the cavity, while the inner side of the lever will similarly contact with the inner side of said cavity, so that the lever is caused, when the projection 11 is moved toward the axis of the trunnion 14, to grip 90 and hold rigidly to the movable element 13 and to release said element when it is moved in the opposite direction.

The cylinder-casting 1 has extending between its extremities at points preferably opposite to those united by the plate 7 the portion 17, which has within it passages 18 and 19, communicating with a valve-chest 20 and also with the interiors of the bushings 3 and 4. A bushing 21, having a flange 22, is held 95 in the valve-chest by means of a coupling-piece 23 screwed upon it, and this coupling-

piece has a passage which in operation is connected to any suitable source of supply for fluid under pressure and communicates with a valve 24, designed to be oscillated within the bushing 21. Said bushing is formed with a shoulder or inwardly-projecting flange adjacent to its flange 22, and the valve 24 is shaped to conform to such construction, being so made that its body projects beyond the end of the bushing for the reception of a two-armed piece or fork 26, keyed thereto by means of a pin 25 and so placed as to extend into the path of motion of a projection 27 from the intermediate portion 6 of the plunger. The valve has in it two independent passages 28 and 29, connected to the source of supply and to the exhaust, respectively, and each opening upon the cylindrical surface of the valve, as shown in Fig. 3, in such manner as to operatively coact with openings 30 and 31 in the bushing 21.

In operation any device or apparatus designed to be rotated (in the present instance a drill) is fixed to the member 13 in any of the well-known ways, and there are, if desired, handles, as shown in full lines at 32, fixed to the bushings 3 and 4, whereby the motor may be held. Fluid under pressure is admitted to the valve-chest through the coupling-piece 23 and passing into the channel 28 of the valve 24 flows, when the parts are in the positions shown in Fig. 3, through the opening 31 of the bushing 21 into the port 18 and through the opening in the bushing 3 into the clearance-space between the end of said bushing and the plunger 5. The result of this admission of fluid is to force the plunger toward the open end of its cylinder-bushing 3, such action turning both of the arms 10 on their pivots 9 and causing the pin of the lever 12 to be moved in the slot of the arm 10 outwardly toward the pivot thereof, consequently placing said lever in such position within the annular cavity of the member 13 that it slips through the same for a limited distance. The motion of the arm 10^a on its pivot will cause the projection 11 of the lever 12^a to move toward the plunger, thereby causing said lever to grip or jam between the inner and outer faces or sides of the cavity 13^a and causing a partial revolution of the member 13 as the plunger 5 is moved. Just before said plunger arrives at the end of its stroke toward the bushing 4 the projection 27 on its intermediate section 6 strikes one arm of the fork 26 and moves it so as to oscillate the valve 24, so that the opening 31 in the bushing 21, port 18, and the interior of the bushing 3 are placed in communication with the exhaust through the passage 29 of said valve. At the same time the opening 30 in the bushing 21, port 9, and the interior of the bushing 4 are placed in communication with the source of fluid-supply, with the result that the direction of motion of the plunger is reversed and is at the proper time driven toward and into the bushing 3. Such action causes the lever 12 to grip the sides of

the cavity 13^a, while the lever 12^a is moved backwardly, so that it passes through the said cavity without gripping the walls thereof. The member 13 is thus intermittently rotated, being given two impulses in the same direction for each complete cycle of movements of the plunger, the power being transmitted through the clutching device formed by the arms 10 and 10^a, levers 12 and 12^a, and the gripping portion of the element 13.

If desired, I may provide any desired form of shoes or gripping-pieces 33 on the gripping-faces of the levers 12 and 12^a, thereby preventing excessive wear of these parts.

I claim as my invention—

1. The combination in a motor, of a reciprocating driving element, a rotary element, and means connecting said two elements including a device having a lever or levers constructed to automatically grip and release said rotary element when the driving element is reciprocated, substantially as described.

2. The combination in a motor, of a reciprocating element, a rotary element, a clutch connected thereto and a pivoted lever connecting the clutch to the reciprocating element, with means operated by said reciprocating element for controlling the action thereof, substantially as described.

3. A motor having a cylinder, a reciprocable plunger therein, valve mechanism controlling the admission of fluid to said cylinder, a rotary element and a clutch operative thereon, with means, including an arm, in movable engagement with one member of the clutch for connecting said clutch with the plunger and constructed to intermittently actuate said clutch when the plunger is operated, substantially as described.

4. The combination of a supporting-frame, a cylinder thereon, a plunger operative in the cylinder, an arm pivoted to the frame and engaging the plunger, an element rotatably supported on the frame, and a clutch including a lever in engagement with the arm for connecting said arm with said rotatable element, substantially as described.

5. The combination of a frame, a cylinder thereon, a plunger in the cylinder, a rotatable element on the frame, an arm pivoted to the frame, and engaging the plunger, and a lever engaging the arm and constructed to grip the rotatable element when moved by said arm, substantially as described.

6. The combination of a frame having a cylinder, a plunger operative therein, a movable arm engaging said plunger, a rotatable element having within it an annular recess, and a lever in said recess in engagement with said arm and free to be moved thereby so that it will grip said rotatable member, substantially as described.

7. The combination with a frame, a cylinder thereon, a plunger in the cylinder, a trunnion on the frame, a rotatable element carried on said trunnion having a gripping-surface, an arm connected to the plunger and a

- lever movably engaging said arm and free to be moved so as to grip or release said rotatable piece, substantially as described.
8. The combination of a frame, two cylinders thereon, a plunger having portions operative in said cylinders, a rotatable piece carried by the frame, an arm pivotally attached to the frame and engaging the plunger and a piece in engagement with the frame and free to grip or release the rotatable element substantially as described. 50
9. The combination of a cylinder having a plunger therein, a rotary element, means operatively connecting the plunger with said rotary element, a valve-chest for the cylinder, an externally-flanged cylindrical bushing in said valve-chest, a piece engaging said bushing for retaining it in position, an internally-projecting flange on the bushing and a valve confined between said flange and the piece for holding the bushing in position, with means for operating said valve from the plunger, substantially as described. 55
10. The combination of a frame having upon it a cylinder, a plunger in the cylinder, means for causing operation of said plunger, a rotatable member having within it an annular recess, a lever in said recess, and an arm pivotally fixed to the frame and in engagement with the plunger, with means for connecting said arm and the lever, substantially as described. 60
11. The combination of a frame having on it two cylindrically-bored bushings closed at one end, a plunger operative in said bushings, a trunnion projecting from the frame, a member supported on said trunnion so as to be free to rotate, an arm pivotally attached to the frame and engaging the plunger, with a piece in engagement with the plunger and free to be moved thereby so as to grip or release the rotatable member, substantially as described. 65
12. The combination of a frame having two cylinders, a plunger having parts operative in said cylinders, arms pivoted to the frame and connected to the plunger on opposite sides thereof, a rotatable element supported so as to turn on an axis at right angles to the line of action of the plunger, with a shoe connected to each arm and free to alternately grip and release the rotatable element as the plunger is reciprocated, substantially as described. 70
13. The combination of a frame having a cylinder, a plunger reciprocable therein, a rotary element, a piece free to move bodily around the axis of said rotary element and having a portion also free to move radially of said axis whereby it may be caused to grip the rotary element, with means for connecting said piece and the plunger, substantially as described. 75
14. The combination of a cylinder, a plunger reciprocable therein, a rotary element having an annular portion, a piece free to move on the annular portion, an arm operatively connected to the plunger and provided with means for positively moving a portion of said piece radially of said rotary element to cause it to grip or release the latter, substantially as described. 80
15. The combination of a frame having a cylinder, a reciprocable plunger, a rotary element having an annular recess, a lever or levers movable within said recess, a slotted arm pivotally attached to the frame, and operatively connected to the plunger, said lever or levers having portions engaging the slot in said arm, substantially as described. 85
16. The combination of a frame having a cylinder, a reciprocable plunger therein, a rotary element supported on the frame, a curved bar having gripping-surfaces on opposite sides placed to coact with suitable portions of the rotary element, a pivotally-supported arm constructed to engage said bar and having means for moving it so that it grips the rotary element, said arm also engaging said plunger, substantially as described. 90

In testimony whereof I have signed my name to this specification in the presence of two subscribing witnesses.
